(57) **CLAIM**

The ornamental design for a clip, as shown and described.

DESCRIPTION

FIG. 1 is a perspective view viewed from lateral side of a clip showing our new design;
FIG. 2 is a perspective view viewed from front side thereof;
FIG. 3 is a front elevation view thereof;
FIG. 4 is a right side elevation view thereof;
FIG. 5 is a top plan view thereof;
FIG. 6 is a bottom plan view thereof;
FIG. 7 is a sectional view taken along line VII-VII in FIG. 3;
FIG. 8 is a sectional view taken along line VIII-VIII in FIG. 3;
FIG. 9 is a sectional view taken along line IX-IX in FIG. 5;
FIG. 10 is a reference view showing the state of use; and,
FIG. 11 is a reference view showing the state of use.
The broken lines shown in the drawings represent unclaimed portions of the clip and form no part of the claimed design.
